HAIR CURLER

James K. Crofts, Winston-Salem, N. C.

Application March 4, 1941, Serial No. 381,743

7 Claims. (Cl. 132—41)

This invention relates to hair curlers, and has for one of its objects the production of a simple and efficient hair curler which is so constructed as to firmly grip the hair between the clamping jaws, and which is provided with means for tightly winding the hair about the clamping jaws and holding the hair in this wound position for curling without the necessity of employing additional fastening means to hold the curler in place.

A further object of this invention is the production of a simple and efficient curler having a hair-engaging element rotatably mounted to circle about the hair clamping jaws in a manner to roll the hair upon the jaws and firmly hold the hair in this rolled position for curling without requiring additional locking means, thereby providing an automatic retaining means for the curler.

Other objects and advantages of the present invention will appear throughout the following specification and claims.

In the drawings:

Figure 1 is a side elevational view of the curler;
Figure 2 is a top plan view;

Figure 3 is a longitudinal sectional view taken on line 3—3 of Figure 2;

Figure 4 is a longitudinal sectional view taken on line 4—4 of Figure 3;

Figure 5 is an end elevational view looking at the outer opening end of the curler;

Figure 6 is a vertical sectional view taken on line 6—6 of Figure 3;

Figure 7 is a perspective view of one form of journal for supporting the rotating element;

Figure 8 is a fragmentary side elevational view of one form of rotating element the journals being shown in section;

Figure 9 is a top plan view of the element shown in Figure 8, the journals being shown in section;

Figure 10 is a fragmentary perspective view of a modified form of rotating element and supporting journal and end structure;

Figure 11 is a perspective view of one type of closure spring for the clamping jaws;

Figure 12 is a perspective view of a further type of closure spring for the clamping jaws;

Figure 13 is a side elevational view, partly in section showing a modified form of the invention;

Figure 14 is a top plan view of the structure shown in Figure 13;

Figure 15 is a longitudinal sectional view of

the form of the device shown in Figures 13 and 14 with the rotating element extended;

Figure 16 is a perspective view of the rotating element shown in Figures 13 to 15; and

Figure 17 is a view looking at the inner end of the curler, shown in Figures 13 to 15.

By referring to the drawings it will be seen that 15 designates the primary jaw to which is hingedly connected the secondary jaw 16 by means of a journal pin 17 mounted near one end. The jaw 15 is preferably circular in cross section and the jaw 16 is preferably semi-circular in cross section and is adapted to overlie the primary jaw 15 when in a closed position as shown in Figure 6. These jaws may preferably be formed of aluminum or other suitable lightweight material. The jaw 15 is provided with an angularly extending finger-engaging lip 18 and the jaw 16 is provided with an angularly extending lip 19, the lips 18 and 19 diverging and being carried by the rear ends of the jaws 15 and 16.

A pair of spaced substantially V-shaped flat springs 20 are fitted between the lips 18 and 19, the outer ends of the springs 20 abutting against the inturned flanges 21 formed upon the respective ends of the lips 18 and 19. These springs 20 are adapted to spread the lips 18 and 19 apart to hold the jaws in a yieldable closed position.

A rotating element preferably formed from a wire strand is carried by the journal pin 17 and is rotatably mounted therethrough, and this rotating element comprises a journal shank 22 which is rotatably mounted through the journal pin 17 as above stated, the outer end also being rotatably mounted through a journal pin 23 mounted near the outer end of the primary jaw 15. The end of the shank 22 is bent laterally to provide a stop 24 to limit the movement of the shank 22 in one direction, the shank 22 being also bent laterally beyond the journal pin 17 to provide an abutment shoulder 25. The abutment shoulder 25 is adapted to limit the longitudinal movement of the shank 22 in one direction and the laterally bent end 24 is adapted to limit the longitudinal movement of the shank 22 in the opposite direction. The shank 22 carries a finger-engaging loop 26 at its rear end, which loop overlies the lip 19, as shown in Figures 1 and 3, and may be rotated about the lip 18. The loop 26 carries a hair-engaging shank or finger 27 which extends forwardly and overlies the jaw 16 when the parts are in the position shown in Figures 1 and 3, and this hair-engaging finger or shank 27 is adapted to rotate about the jaws

50 55 60 65 70 75 80 85 90 95

15 and 16 for winding the hair about the jaws 15 and 16.

The hair curler may be placed in position by pressing the lips 18 and 19 together by means of the fingers of the operator and placing the hair between the jaws 15 and 16. The lips 18 and 19 may then be released and the springs 20 will cause the jaws 15 and 16 to firmly clamp the hair therebetween, and the operator may then grip the loop 26 between the fingers and by rotating the loop 25 about the lips 18 and 19 the shank or hair-engaging finger 27 when rotated in the direction indicated by the arrow in Figure 6 will cause the hair to be wound about the jaws 15 and 16 in the manner shown in Figure 6. As soon as this rotation is discontinued the shank or finger 27 will hold the hair in a set wound position without the necessity of employing other fastening means, the position of the parts automatically locking the curler in position.

Various means may be employed for holding the rotating element comprising the shank 22, the loop 26 and shank or finger 27 in rotatable engagement with the jaws 15 and 16, and the journal 23 may be replaced by a suitable journal plate 23a, shown in Figure 7. The shank 22a shown in Figures 8 and 9, which figures illustrate a modified type of shank, may be held against longitudinal movement through the journals 17a and 23b by means of the flattened portions 28 and 29.

As shown in Figure 10 the rotating member may be provided with a shank 22b having an offset portion 30 passing through the journal 17b, and the outer end of the shank 22b may be provided with a laterally coiled terminal 31 to rotate within the outer end of the jaw 15a shown in dotted lines.

As shown in Figure 12 the two spaced springs 20 may be replaced by a single spring 20a having an aperture 32 through which the rotating shank 22c may extend, the shank 22c having an offset portion 25a beyond the spring 20a.

In Figure 11 there is also shown a further modified form wherein a wire spring 33 may be utilized in place of the springs 20 if desired. When the springs 20, as well as the spring 33, are used sufficient space must be provided to permit the rotation of the loop 26 of the rotating element to freely move about the clamping jaws and the lips 18 and 19.

From the foregoing description, it will be seen that a very efficient hair curling device is provided in the nature of the hair clamping jaws which support a rotating element which is carried by and anchored in engagement with the jaws in a manner whereby the rotating element may be rotated about the jaws when the jaws are in a clamped position, the rotating element having a finger-engaging loop to facilitate the rotation of the rotating element and also being provided with a hair-engaging finger or shank for winding the hair about the jaws. This structure also provides an automatic locking means for holding the parts in a set position as soon as rotating movement is discontinued, thereby avoiding the necessity of auxiliary or additional locking means.

By considering Figures 13 to 17, it will be seen that a form of curler is illustrated comprising a tubular primary jaw 35, to which is hingedly connected the secondary jaw 36 by means of oppositely positioned hollow rivets or eyelets 37. The jaw 35 is preferably circular in cross-section and perforated, as shown. The jaw 36 is preferably

semi-circular and is adapted to overlie the primary jaw 35 in a manner similar to the form shown in Figure 6. Each jaw 35 and 36 is provided with a rearwardly extending lip 38 having an inturned flange 39 at its outer end. The jaws 35 and 36 diverge outwardly toward their outer ends, as shown in Figures 13 and 15. A V-shaped spring 40 fits between the jaws 35 and 36 for normally holding the jaws in spread-apart relation, the ends of the spring 40 engaging the flanges 39 and being held in position thereby.

A rotating element is carried by the jaws and comprises a shank portion 41 which extends through the apex of the spring 40 and is journaled therein, as shown in Figure 15. The inner end of the shank 41 carries a spiral coil 42 having a plurality of convolutions of a diameter to snugly fit in the tubular primary jaw 35, to brace the rotating member. A sharp right-angle bend 43 is formed at the junction of the spiral coil 42 with the shank portion 41 to prevent the rotating member from being detached from the spring 40, this bend 43 constituting a stop to limit sliding movement of the shank 41 in one direction. The shank 41 is provided with a finger-engaging loop 44 which terminates in a hair-engaging loop or shank 45, in the nature of an overlying loop snugly engaging the jaw 36 when in one position. This shank 45 is adapted to ride upon the lip 38 of the jaw 36 when the finger-engaging loop 44 is moved away from the jaws 35 and 36 to the position shown in Figure 15, thereby spacing the shank 45 away from the jaw 36. The outer end of the loop or shank 45 is out-turned as shown at 46.

The spiral coil 42 serves to center the rotating member within the tubular shank 35 and holds the rotating member steady at the same time allowing the wire rotating member to be completely formed before extending the rotating member through the apex of the spring 40. When assembling the device the jaws are riveted together, the spring 44 is slipped over the shank 41 by threading the coil 42 through the apertured apex of the spring 40 and the coil is slipped into the tubular primary jaw 35. The spring 40 is then placed between the lips 38 in a position to cause the ends of the spring 40 to abut against the flanges 39. When the rotating member comprising the shank 41 and associated members is drawn to the position shown in Figure 12, the ends of the hair may be caught between the jaws 35 and 36. The whole device is then rotated as far as desired, winding the hair around the jaws and then the wire or rotating member is pushed to the position shown in Figure 13 and then rotated until exactly the right amount of hair is wound upon the jaws where the curler may remain until it is desired to remove the curler from the hair.

When the hair is gripped between the jaws 35 and 36 should any short ends of hair project, and if rotated while in this position, there will be a reverse bend put in the ends of the hair, but by leaving the wire pushed into the tube, as shown in Figure 13, and rotating the wire in the direction of the short ends and around the tube before the hair is rolled upon the tube, the short ends of the hair will be rolled correctly and held until the tube is retained for a sufficient time to hold these loose ends under the rolled hair. The wire or shank 45 thereof may then be withdrawn out of the way and the rolling continued to the desired point. The shank 45 may then be

pushed back in and rotated to the proper holding position.

It should be understood that after the hair has been properly set the curler may be easily removed without disturbing the set curl, and because of the structure of the curler the hair will be smoothed and tightened when wound upon the curler to properly set the curl.

Certain detail changes in the structure may be employed without departing from the spirit of the invention, so long as such changes fall within the scope of the appended claims.

Having described the invention, what is claimed as new is:

1. A hair curling device of the class described comprising a plurality of clamping jaws hingedly connected together, each jaw having a diverging finger-engaging lip at one end, spring means carried by the lips for spreading the lips apart and closing the jaws together, the outer ends of the jaws having inturned flanges to provide abutments for said spring means, means for winding hair about the jaws and for holding the hair in this wound position, said spring means having an aperture, and said last mentioned means passing through said aperture.

2. A hair curler device of the class described comprising a pair of hingedly connected spring-pressed jaws, a rotating element carried by the jaws and having a hair-engaging finger mounted for rotating movement about the jaws and adapted to engage hair and wind the hair about the jaws, and being also adapted to automatically hold the device in a set position when rotation of the rotating element is discontinued, said rotating element having a yieldable finger-engaging means extending beyond the jaws at one end to facilitate the rotation of the rotating element and yieldable under pressure of the opening of the jaws, and said rotating element extending substantially the full length of said jaws and lying in close proximity to the jaws to frictionally hold the rotating element in a set position when rotation is discontinued.

3. A hair curler device of the class described comprising a pair of hingedly connected spring-pressed jaws, a rotating element carried by the jaws and having a hair-engaging finger mounted for rotating movement about the jaws and adapted to engage hair and wind the hair about the jaws, and being also adapted to automatically hold the device in a set position when rotation of the rotating element is discontinued, said rotating element having a finger-engaging means extending beyond the jaws at one end to facilitate the rotation of the rotating element, journals carried by said jaws, and means carried by the rotating element for limiting longitudinal movement of the rotating element through the journals while permitting rotatable movement within the journals.

4. A hair curler of the class described comprising a pair of hingedly connected spring-pressed jaws, a rotating element carried by the jaws and having a hair-engaging finger mounted for rotating movement about the jaws and adapted to engage hair and wind the hair about the jaws, and being also adapted to automatically hold the device in a set position when rotation of the rotating element is discontinued, said rotating element having a finger-engaging means extending beyond the jaws at one end to facilitate the

rotation of the rotating element, means for limiting the longitudinal movement of the rotating element within the jaws, and guiding means formed at the end of the rotating element and rotatable within the jaws for bracing the outer end of the rotating element.

5. A hair curler of the class described comprising a pair of hingedly connected spring-pressed jaws, a rotating element carried by the jaws and having a hair-engaging finger mounted for rotating movement about the jaws and adapted to engage hair and wind the hair about the jaws, and being also adapted to automatically hold the device in a set position when rotation of the rotating element is discontinued, said rotating element having a finger-engaging means extending beyond the jaws at one end to facilitate the rotation of the rotating element, means for limiting the longitudinal movement of the rotating element within the jaws, guiding means formed at one end of the rotating element and rotatable within the jaws for bracing the outer end of the rotating element, and said guiding means comprising a laterally coiled terminal.

6. A hair curler of the class described comprising a pair of hingedly connected spring-pressed jaws, a rotating element carried by the jaws and having a hair-engaging finger mounted for rotating movement about the jaws and adapted to engage hair and wind the hair about the jaws, and being also adapted to automatically hold the device in a set position when rotation of the rotating element is discontinued, said rotating element having a finger-engaging means extending beyond the jaws at one end to facilitate the rotation of the rotating element, means for limiting the longitudinal movement of the rotating element within the jaws, guiding means formed at one end of the rotating element and rotatable within the jaws for bracing the outer end of the rotating element, said guiding means comprising a laterally coiled terminal composed of a plurality of convolutions of a diameter to snugly fit within one of the jaws to guide the rotating element in its sliding movement.

7. A hair curler of the class described comprising a pair of hingedly connected spring-pressed jaws, a rotating element carried by the jaws and having a hair-engaging finger mounted for rotating movement about the jaws and adapted to engage hair and wind the hair about the jaws, and being also adapted to automatically hold the device in a set position when rotation of the rotating element is discontinued, said rotating element having a finger-engaging means extending beyond the jaws at one end to facilitate the rotation of the rotating element, the jaws being diverging lips, a V-shaped spring engaging the lips and normally holding the lips in spread-apart relation, said rotating element having a shank extending through the apex of the spring, an abutment shoulder formed at substantially right-angles to the shank to limit longitudinal movement of the shank in one direction, one of the jaws being circular in cross-section, and a spiral coil carried at one end of the shank, the coil comprising a plurality of convolutions of a diameter to snugly fit within one of the jaws to guide the rotating element in its sliding movement.

JAMES K. CROTT.
